UNITED STATES PATENT OFFICE

SEBASTIANO MAGNANO, OF LAWRENCE, MASSACHUSETTS, ASSIGNOR TO MAGNANO CORPORATION, OF LAWRENCE, MASSACHUSETTS, A CORPORATION OF MASSACHUSETTS

TEXTILE APPARATUS

Application filed August 28, 1929. Serial No. 283,972.

This invention pertains to apparatus for associating warp yarns or threads with detached loom elements, such for example as stop motion drop pins or wires, and more particularly to apparatus of the general type disposed in the patent to Dustin, No. 1,072,103, September 2, 1913 and in my prior patents No. 1,512,704, dated October 21, 1924, No. 1,516,675, dated November 25, 1924, No. 1,530,605, dated May 24, 1925, and No. 1,584,236, dated May 11, 1926, and constitutes an improvement upon the apparatus disclosed in said patents.

In my copending application, Serial No. 335,190 filed January 26, 1929, I have disclosed mechanism having the same general purpose as that of the aforesaid patents, but simplified and reduced in size and having a single movable magazine for drop wires adapted to deliver wires in a plurality of banks, together with means for selecting and accurately positioning the yarns for the reception of the wires.

I have now devised drop wire distributing mechanism of further improved construction, even simpler than that disclosed in my aforesaid applications, which is cheaper to construct and lighter in weight, and which is distinguished from the prior apparatus among other things in the substitution of spring means for advancing the magazine carriage, and for compacting the wires within the magazine. These and other features of improvement will be described more specifically hereinafter by reference to the accompanying drawings in which a preferred embodiment of the invention is illustrated by way of example, and in which:

Fig. 1 is a front elevation of the apparatus showing the supporting rails in vertical section;

Fig. 2 is a rear elevation of the apparatus shown in Fig. 1;

Fig. 3 is a plan view of the same apparatus;

Fig. 4 is an elevation of the left-hand end of the machine as viewed in Fig. 1;

Fig. 5 is a fragmentary section, with certain parts omitted, on the line 5—5 of Fig. 1;

Fig. 6 is a fragmentary vertical section substantially on the plane of the line 6—6 of Fig. 4 omitting certain parts;

Fig. 6^a is a fragmentary section substantially on the line 6^a—6^a of Fig. 6;

Fig. 7 is a fragmentary section on the line 7—7 of Fig. 1;

Fig. 8 is a bottom plan view of certain yarn manipulating devices shown in Fig. 5;

Fig. 9 is a fragmentary perspective view illustrating the thread separating and retaining means;

Fig. 10 is a view similar to Fig. 9 but showing the same parts in another position, together with associated parts;

Fig. 11 is an end elevation of the right hand end of the machine, omitting certain parts;

Figs. 11^a and 12 to 17 inclusive are fragmentary elevations from the left end of the machine illustrating the several steps in the process of separating the yarn and placing a wire thereon;

Fig. 18 is a fragmentary horizontal section substantially on the line 18—18 of Fig. 3;

Fig. 19 is a composite view showing the follower block of the magazine in side and end elevation respectively;

Fig. 20 is a side elevation of one of the wire-receiving fingers; and

Fig. 21 is a side elevation of one of the guard members associated with the receiving fingers.

Main frame and drive

Referring to the drawings (Figs. 1, 2, 3 and 4) the frame of the machine comprises the left end member or head 1 and the right end member 2, the latter preferably being of substantially inverted U-shape. Front and rear rails 3 and 4 respectively connect the left and right end members. The end members 1 and 2 are provided with brackets carrying front supporting rolls 6 and 7, and with rearwardly extending brackets having aligned bearings for a shaft 8 to which are fixed the rear supporting rolls 9 and 10. The rolls 6 and 9 are designed to rest upon a rail 14^a while the rolls 7 and 10 rest upon a rail 14^b.

a rail 15^a. These rails may be considered as parts of the present machine and are placed upon the loom frame only when needed. If desired, and as shown and described in my aforesaid application, the rolls 9 and 10 may be provided with toothed or gear portions and the rails may be furnished with corresponding racks with which such gear portions of the rolls mesh, thus preventing slippage between the rolls and rails. Preferably the shaft 8 is provided with a hand wheel 20 for turning it manually, thus permitting the machine to be moved along the rails whenever desired.

15 Provision is also made for moving the machine automatically step by step along the rails 14^a and 15^a in order to position the machine for application of drop wires to successive groups of warp threads. For the 20 purpose of moving the machine automatically, the shaft 8 is extended to the left of the end frame or head 1 and carries a ratchet wheel 21. Shaft 8 also carries a sleeve 22 (Fig. 3) free to turn upon the shaft and 25 having arms 23 and 24 (Fig. 4) projecting at substantially right angles to each other. A feeding pawl 25 is pivotally mounted at 26 at the lower end of the arm 24 and this pawl is provided with an arm 27 to which 30 the upper end of a link 28 is pivotally connected. The lower end of the link 28 carries a bracket 29 to which is connected the stem 30 of a detector or feeler member 32 which is adapted to rest upon and be supported by the set of warp threads. The 35 stem 30 is guided in a fixed member 31 projecting from the frame member 1, and at a point below the bracket 29 the stem 30 passes loosely through an opening in a lifter 40 lever 33 secured to the end of a lifter lever 34 pivotally united at 35 to a boss on the frame 1.

A spring 39 tends to raise the lever 34, the latter being provided with a cam follower 36 which engages a controlling cam (not shown) upon a shaft 38. The shaft 38 is journaled at its right hand end (Fig. 1) in a suitable bearing in the end frame 1 and at its left hand end in a bearing provided 50 at the lower end of a bracket 40 projecting outwardly and downwardly from the end frame member 1. The shaft 38 is furnished with a sprocket wheel 41 which receives a driving chain 42 engaging a sprocket wheel 43 fixed to a main drive shaft 44. This main shaft is journaled near its left hand end (Fig. 1) in a bearing opening in the end frame 1 and near its other end in a bearing provided in the end frame 2. An intermediate bearing is provided in a bracket 45 secured to the front rail 3.

A link 49 (Fig. 4) is pivotally secured to the arm 23 of the sleeve 22 and at its lower end the link 49 is pivotally connected at 50 (Fig. 2) to a lever 51 pivotally mounted

on the pin 35 above referred to. This lever 51 carries a cam follower which engages a cam (not shown) mounted on shaft 38. A spring 54 (Fig. 1) connected to lever 51 holds the follower in contact with the cam. 70

A bracket 55 attached to rail 3 supports a casing 59 which houses reduction gearing of any usual type adapted to transmit motion from the shaft of an electric motor 60, also supported by bracket 55, to a gear 61 fixed to the main drive shaft 44. Suitable controlling switches for the motor will be described hereinafter. 75

Thread manipulating mechanism

80 A horizontal stub shaft 74 (Fig. 2) projects outwardly from the end member 1 and supports a lever 77. (Figs. 2, 4 and 10.) A spring 79 (Fig. 2) secured at one end to lever 77 and at its other end to a bar 80 projecting from bracket 40 tends to swing the lever 77 upwardly in a counterclockwise direction as viewed in Fig. 4. The lever 77 has a cam follower roll 89 (Fig. 2) which engages a cam 90 (Figs. 1 and 4) mounted on the shaft 38. The lever 77 has an opening for the reception of the upper end of a holdback finger 91 which is adjustably secured in position by means of a suitable set screw or the like. The lower end of this holdback finger is provided with a hook 92 for engagement with the warp threads as hereinafter more fully described. 85

The bracket 40 is provided with a lateral arm 40^a (Fig. 4) carrying a stub shaft on 100 which is pivotally mounted a lever 94. This lever is furnished with a cam follower roll 103 which is held in engagement with a cam 104 on the shaft 38 by means of a spring 105 attached at its upper end to a pin projecting from bracket 40. The lever 94 is provided with an opening for the reception of the upper end portion of a second holdback finger 105^a which is adjustably secured in position by appropriate means, and which has a hook portion 107 (Figs. 4 and 10) at its lower end. 105

The cams 90 and 104 are spaced apart on the shaft 38 and between them a sleeve 108 (Figs. 1, 9 and 10) is fixed to the shaft. The sleeve is provided with oppositely extending arms 109 and 110 (Fig. 10) having end portions 111 and 112 respectively disposed in substantially parallel planes. Blade carriers 113 and 114 are adjustably secured to the members 111 and 112 and each blade carrier supports a thin resilient warp separating blade 116 and 116^a, respectively. 115

A bracket 118 (Figs. 2 and 4) depends from the inner face of end frame 1 and supports a bridge member 121, while a bracket 120 (Fig. 2) attached to the rear rail 4 supports a second bridge member 122 (Fig. 1). Duplicate thread guiding and manipulating mechanisms are carried by the re- 125

spective bridge members and for purposes of description it is necessary to refer only to the instrumentalities carried by bridge member 121, for which reference may be had 5 particularly to Figs. 4, 5 and 8.

Preferably each bridge member carries a yarn guide G which may be of polished steel or other material having a smooth and preferably rounded lower edge 123 whose central portion is substantially horizontal and lies in a plane slightly below the normal plane of the sheet of warp threads. At their rear ends the lower edges of these guides G curve upwardly, and the guides terminate 10 in horns 124 adapted to engage the forward threads of the warp set and to assist in guiding the threads downwardly into contact with the horizontal edge portions 123 of the guides.

Preferably each yarn guide member G has an auxiliary guide member G¹ adjustably held in position by means of a screw 123^a, (Fig. 4) and having a substantially vertical end surface 123^b constituting a yarn retainer. The lower edge of the auxiliary guide G¹ is smoothly rounded like that of the main guide G, and by swinging the auxiliary guide about the screw 123 as a center, its lower corner 123^c may be adjusted with reference to the plane of the edge 123 of the main guide. While such adjustment of the member G¹ is desirable, it is not always necessary, and if desired the retainer surface 123^b may be formed directly upon the main 35 guide.

The thread positioning instrumentalities carried by each bridge member include a thread "positioner" comprising a lever 125 (Fig. 5) having a thread engaging and positioning surface 126. This lever is pivotally supported upon a stud 127 projecting from the corresponding bridge member. A second lever provided with a hook-like lower end 128 (constituting a thread engaging "clamp" 40 for clamping the thread against the positioning surface 126) is also pivotally supported by the stud 127.

A lever 129 having a curved lower end which is hereinafter termed a "pusher" is pivotally supported upon a stud 129^a projecting from the bridge member. The levers 125 and 129 are connected by a link 130 so that movement of the lever 125 is imparted to the lever 129. The point of connection 45 of the link 130 to the lever 129 is nearer to the fulcrum of the latter than is the point of connection of the link 130 to the fulcrum of the lever 125. It thus follows that the lever 129 will swing more rapidly than the lever 125.

Links 131 and 132 (Fig. 5) connect the levers 125 and 128, respectively, to one end of a bell crank lever 133 pivotally supported upon a stub shaft 134 projecting from the bridge member. This bell crank lever has

an upwardly projecting arm 135 which is provided with a stud 137 carrying a cam follower roll 138 engaging a cam 139 fixed to the main drive shaft 44, it being understood that a similar cam 139 is provided for actuating the thread manipulating instrumentalities of each bridge member. A spring 135^a attached to each lever 135 holds the corresponding roll 138 against its cam 139.

A bracket 140 (Figs. 1 and 7) is secured to the front rail 3 adjacent to the head member 1, and has an arm 141 (Fig. 7) which supports a stud 142 upon which is pivoted a lever 143. This lever is provided with a cam follower roll 144 which engages the periphery of a cam 145 fixed on the shaft 44. A spring 146 attached to an arm 147 of lever 143 keeps the roll 144 in proper engagement with the cam. The lever 143 has an opening in which is adjustably secured the upper end of a "looper" member 148 having a curved yarn engaging lower end 149 which moves from front to rear in a vertical plane intermediate the head member 1 and the bridge member 121.

The magazine carriage

The magazine and associated mechanism for applying the drop wires is supported by a reciprocating carriage comprising the right-hand member 150 (as viewed in Fig. 3) and the left-hand member 151, and the front and rear rails 152 and 153 respectively. The carriage is supported to reciprocate upon the front and rear rails 3 and 4 of the main frame by means of flanged rolls 154 and 155. To assist in guiding the carriage, and to hold it steady upon the rails, I provide hold down rolls 156. As shown, 50 these latter rolls are carried by the upwardly projecting arms of a U-shaped bracket 157 (Figs. 1 and 11) attached to the rails 3 and 4 at the right-hand end of the main frame.

A bracket 158 (Fig. 1) is attached to the front rail 3 in the space between the head 2 and the bracket 157, and this bracket 158 is provided with a downwardly directed web 159, (Fig. 11) carrying a bearing boss 160 aligned with a boss 161 carried by a downwardly directed arm 162 of the bracket 157. These bosses 160 and 161 support a stub shaft 163, upon which is pivotally mounted the lower end of the carriage actuating lever 164. This lever has a cam follower roll 165 (Figs. 1 and 11) engaging the periphery of a cam 166 fixed to a transverse shaft 167 (Figs. 1 and 2) carrying a beveled gear 168 (Fig. 2) which meshes with a beveled pinion 169 fixed to the rear end of the shaft 44. The bracket 158 is bifurcated to provide spaced arms, each carrying a bearing for the shaft 167, and between which the gear 168 is located. In order to 100 105 110 115 120 125 130

provide additional support for the shaft 167, its rear end is mounted in a bearing in a bracket 169^a (Fig. 2) attached to the rear rail 4.

5 The cam 166 is given the proper peripheral contour to effect the desired sequence of positions of the carriage for the placing of successive drop wires, and this cam may be interchanged for cams of other shapes, 10 if desired. As here shown, the machine delivers two drop wires for each rotation of the shaft 44, and as the ratio of the gear 168 to the pinion 169 is as two to one, it is evident that during each complete rotation 15 of the cam 166 four wires are delivered, the cam being shaped to place the carriage in a different position as each of the four wires is delivered.

20 The lever 164 carries a post 170, preferably provided with a spline 171, (Fig. 2) and upon this post a split bracket 172 is adjustably secured. This bracket carries a stud 173 (Fig. 2) to which is pivotally secured one end of a connecting rod 173^a of 25 adjustable length. The other end of rod 173 is pivotally secured to a stud 174 (Fig. 1) carried by a split bracket 175, (Fig. 2) adjustable upon a post 176 fixed in a bracket 177 attached to the end member 151 of the 30 carriage, said post 176 preferably having a spline 178 to prevent the bracket from turning on the post.

35 A bracket 179 (Fig. 1) secured to the left end member 150 of the carriage is provided with a hook 180 which receives a flexible cord, cable or chain 181 (here shown as a wire cable 181) whose ends are wrapped around and attached to a drum 182 (Fig. 3) fixed to a shaft 182^a (Fig. 1) journaled in 40 a spring drum housing 183 secured to the end member 1 of the main frame. This housing 183 encloses a coiled spring 183^a (Fig. 1) which tends to turn the shaft 182^a in a counterclockwise direction, as viewed in 45 Fig. 1, so as to wind up the cable 181 on the drum, thus tending to move the carriage to the left whenever such movement is permitted by the cam 166, the spring yielding to allow movement of the carriage in the 50 opposite direction. By changing the positions of brackets 172 and 175 and the length of rod 173^a the extent of travel of the carriage can be varied.

55 The magazine

The magazine and wire delivery means is of the general type disclosed in my copending application above referred to, and to which reference may be had for certain of 60 the less material details. This magazine comprises essentially a substantially horizontal bar 184 (Figs. 3, 5, 6, 6^a and 18) which is narrow transversely to permit drop wires to be straddled over it so as to rest 65 suspended upon its upper edge, but which is

deep vertically so as to form a guide for the depending legs of the drop wires, thereby to prevent the wires from tipping sidewise. This magazine bar 184 is provided at its right-hand end with a lug 185 (Fig. 18) 70 which is pivotally connected to the lower end of a rod 186. The end member 151 of the carriage is provided with a recess 187 for the reception of the rod 186 whose upper end passes through a vertical bore in the 75 upper wall of the recess. A spring 188 disposed within the recess bears against a shoulder at the lower part of the rod, and tends to move the latter downward, together with the end of the bar 184. This movement is limited by a nut 189 resting upon the 80 upper surface of the end member 151 and having screw-threaded engagement with the rod 186.

Near its opposite end the bar 184 is provided with a downwardly directed leg 190 (Fig. 6) having a vertical slot 191. The leg 190 is disposed in a vertical slot in a bracket 192 (Figs. 2 and 5) depending from the carriage, and the bar is held in adjusted 90 position at this end by means of a bolt 193 passing through openings in the bracket and through the slot 191 in the leg 190.

The delivery end of the bar 184 is disposed opposite to a vertical slot 194 (Fig. 6^a) in the left end member 150 of the carriage. The inner face of the end member 150 is preferably provided with an accurately machined liner plate 195, to which parallel ribs 196 and 197 are adjustably secured, 100 these ribs being spaced apart to provide a chamber 198 constituting the end of the drop wire magazine. The end member 150 of the carriage is provided with vertical guides 199 and 200 spaced from its outer face, and a 105 picker carriage 201 is arranged to reciprocate vertically between the outer face of member 150 and the guide bars 199, 200. This carriage has a picker block 202 (Fig. 6^a) which projects through the slot 194 and is provided at its inner face with an accurately spaced surface for engagement with the last drop wire in the magazine, said surface being spaced from the end of the bar 184 a distance slightly greater than the 110 thickness of a drop wire. A picker element (not shown) of suitable form, such for example as is disclosed in my copending application aforesaid, projects from this finished surface of the picker block, said picker element extending outwardly to a distance not greater than the thickness of a drop wire, and preferably slightly less so as to insure its engagement with but a single drop wire at a time.

115 A lug 203 (Figs. 6 and 6^a) is secured to the picker block carriage 201 and has pivotally connected thereto a yoke 204 to which the lower end of a connecting rod 205 is adjustably attached. The upper end of rod 120 125

205 is secured to a bracket 206 (Figs. 1 and 6) journalled upon a crank pin 207 projecting from a crank disc 208 fixed to a shaft 209 turning in bearings in a bracket 210 (Fig. 4) and which projects upwardly from the end member 150 of the carriage. A cam 211 is fixed to the crank disc 208 and a sprocket wheel 212 is mounted on the rear end of the shaft 209. This sprocket wheel receives a chain 213 (Figs. 2 and 4) passing around a sprocket wheel 214 (Fig. 2) upon a transverse shaft 215 (Figs. 1 and 6) journalled in spaced bearing brackets 216, one of which is shown in Fig. 2 projecting downwardly from the head 150. Between its bearings the shaft 215 carries a large feed roll 217 (Fig. 6) which cooperates with a small feed roll 218 to complete the withdrawal of wires from the magazine.

20 The small feed roll 218 is carried by a shaft 219 journalled in a yoke 220 (Fig. 5) which is pivotally supported by a shaft mounted at one end in a bracket 221 (Fig. 2) projecting downwardly from the head member 150, and at its other end in a rigid arm 222 secured to the bracket 192 by the bolt 193. Springs 223 (Fig. 6) interposed between the yoke member 220 and the bracket 192 tend to move the yoke in a clockwise direction, as viewed in Fig. 6, and therefore to keep the roll 218 in operative relation to the roll 217. The shaft 219 is provided with a pinion 224 (Fig. 2) which meshes with a gear 225 on the shaft 215 of the large feed roll 217, the ratio of diameters of the pinion and gear being substantially the same as that of the large and small feed rolls. The forward end of the shaft 215 carries a beveled gear 226 (Fig. 1) which meshes with a similar beveled gear 227 having an elongate hub which turns and slides freely on the shaft 44. This hub is journalled in a bearing 228 supported by a bracket 229 projecting downwardly and forwardly from the head member 150. This bearing 228 is designed to permit free rotation of the hub of the gear 226 but to prevent endwise movement of the hub relative to the bearing. If desired, a ball bearing ring may be provided to take up end thrust between the gear 227 and the bearing. A spur gear 230 is secured to the gear 227 and in all positions of the carriage meshes with an elongate pinion 231 carried by a shaft having bearings in brackets 232 and 233 attached to the front rail 3 of the main frame. This shaft carries a pinion 234 (Fig. 1) meshing with a gear 235 fixed to a shaft 44.

20 For advancing the wires in compact relation along the magazine bar 184, I provide a pusher block 262 (Figs. 1 and 19) preferably having a curved face 263 for engagement with the last drop wire in the magazine and having spaced legs 264 adapted to straddle the magazine bar 184. This block is

provided with notched lugs 265 adapted to retain a bight of a flexible cord or cable 266 which extends to the right (Fig. 3) in the form of runs disposed at opposite sides of the bank B of drop wires mounted on the bar 184. These runs of cable pass around guide pulleys 267 (Fig. 3) mounted on studs projecting from the inner surfaces of the carriage rails 152 and 153, and then extend to the left (Fig. 3) and have their ends attached to a drum 268 (Figs. 3 and 11) mounted on a shaft 269 turning in bearings in brackets 270 and 271 attached respectively to the rails 153 and 152. The bracket 271 carries a housing for a coiled spring 272 (Fig. 1) which tends to turn the shaft 269 with the drum 268 in a clockwise direction, and thus to wind up the cable 266 so as to urge the pusher block to the left, thereby resiliently compressing the wires forming the bank B, forcing and urging the wires along the magazine rail toward the picker device. To prevent the endmost wire in the magazine from rising as the picker moves up, I provide an adjustable guard member 273 conveniently secured to the bracket 179 carried by the head 151.

20 To assist in accurately placing the wires as delivered by the feed rolls, I provide a chute 250 (Fig. 1) supported upon a shaft 251 journalled in a boss 252 carried by the bracket 221. This chute has a centrally disposed longitudinal rib 253 on its face (Fig. 1) adapted to enter between the legs of a descending drop wire and to guide the wire accurately in its descent. The upper end of the chute is disposed slightly to one side of the bight of the feed rolls so that as a wire W is delivered by the rolls its advancing end will engage the inclined surface of the chute. The shaft 251 carrying the chute 250 is provided at its end with an arm 254 (Fig. 2) which engages a cam 255 on the face of the gear 225. A spring 256 coiled about the chute supporting shaft 251 keeps the arm 254 in contact with the cam. Thus at each rotation of the large feed roll 217 the chute is rocked.

20 If the wires were permitted to slide down the chute directly onto the yarn, the weight and momentum of a wire might be sufficient to break the yarn. To prevent this, I provide rigid supporting means adapted to receive the moving wire, and from which the wire is subsequently delivered to the yarn with a minimum degree of shock. This supporting means preferably comprises a fixed substantially horizontal shaft 257 (Figs. 1 and 2) supported by the bridge members and carrying a plurality of adjustable brackets 258 corresponding in number to the desired number of banks of wires to be placed upon the warp. Each bracket carries a supporting finger 259 having an

upper edge portion 260^a (Fig. 20) upon which the wire is initially deposited. The outer end 261 of the finger is disposed at a slightly lower level than the edge 260^a, and as the wire with the yarn between its legs is moved along the edge 260^a by the action of the yarn manipulating instrumentalities, the wire gradually moves down onto the part 261 which lies substantially in the plane of, or slightly below, the plane of the yarns as defined by the lower edges of the guide members G, so that the weight of the wire is transferred to the yarn gradually and without shock.

In order accurately to deliver the wires onto the vertical supporting fingers 259, I provide the chute 250, at opposite sides of the rib 253, with wire-engaging surfaces which are disposed at different inclinations so that as the wire descends, the ends of its legs are spaced to admit the edge of the supporting finger 259 between them. To prevent the wire thus sprung out of its normal plane from snapping out of control when its upper end is released from the feed rolls, I prefer to provide an inclined guard plate 260 (Fig. 1) at one side of each supporting finger. These guard plates are carried by brackets mounted on the shaft 259 and are so disposed that as the elevated leg of the wire advances, it may engage the guard plate and thus be flexed downwardly so that when its upper end is released, the wire will drop safely upon the supporting arm.

Stop motion

The motor is controlled by a switch device 236 carried by a bracket secured to the rail 153 of the carriage. This switch may be of any suitable type, but preferably employs a starting button 237 and a stopping button 238 (Fig. 3). For convenience in operating these buttons, I provide levers 239 and 240 respectively, mounted on a stub shaft carried by a bracket 241. Preferably the stop lever 240 carries an adjustable contact screw 242. A bell crank lever 243 (Fig. 2) is pivotally supported upon a stub shaft 244 projecting from the switch carrying bracket and has an upwardly directed arm supporting a rocker lever 245. This lever 245 has at one end a cam follower roll 246 which is held in contact with the cam 211, above described, by means of a spring 245^a. The opposite end of the lever 245 is widened at 247 to provide an actuator, engageable under certain circumstances with the top of the screw 242 whereby to depress the lever 240 and the button 238, thereby to stop the motor.

The lever 243 has a depending arm 248 which engages an upwardly projecting finger 249 carried by the yoke 220 (Fig. 6) which supports the small feed roll 218. Nor-

mally when wires are being delivered in orderly sequence by the picker and feed rolls, the succession of wires holds the feed rolls apart a distance equal to the thickness of the wire. When so separated, the finger 249, acting on the arm 248, holds the lever 243 in such position that when the lever 244 is rocked by the cam 211, the actuator 247 fails to engage the screw 242, but if for any reason the wires fail to feed between the feed rolls, the springs 223 move the yoke 220 toward the main feed roll, thus causing the finger 249 to move away from the arm 248, permitting the spring 245^a to swing the arm 244 bodily to the left as viewed in Fig. 2 until the actuator 247 lies above the screw 242. Upon the next downward movement of the actuator by the cam 211, the stop lever 240 and the button 238 are depressed, and the motor is stopped.

The operation of the mechanism is substantially as follows, it being assumed that the rails 14^a and 15^a which support the mechanism are disposed transversely of the yarns of the warp sheet; that the magazine bar 184 has been supplied with a quantity of drop wires forming a compact bank B, which is urged lengthwise of the bar toward the picker block 202 by the pusher 262 and the spring 272; that a drop wire W (Fig. 6) has been fed downwardly between the rolls 217 and 218 so as to hold the rolls in spaced relation with the supporting bracket 220 for roll 218 positioned to cause the lever 243 to withdraw the actuator 247 from above the screw 242; that the feeler 32 is supported by threads of the warp sheet so as to hold the feeding pawl 25 out of operative position; and that the separating blades 116 and 116^a are disposed to turn in the vertical plane of the crossing of the leased warps. It is also assumed that the warps are leased substantially as disposed in my patent No. 1,516,675 dated November 25, 1924 by the use of large lease rods L¹, L², (Fig. 10) and small lease rods 1¹, 1², the large lease rods keeping the upper and lower warp sheets S¹, S² spaced apart a sufficient distance for proper operation of the hold-back fingers 91 and 105^a, while the small lease rods provide a sharp and definite crossing point for the warps, accurately disposed in the vertical plane of rotation of the separator fingers 116 and 116^a. It is further assumed that the picker block 202 is near the upper end of its stroke, and that the first warp *a* (Fig. 10) of the upper sheet S' at the left, (as viewed in Fig. 10) has been separated from the main body of the warps and has been provided with a drop wire W'. The hold-back member 105^a is now engaging the next warp *a'* of the sheet S', while the separator finger 116^a has come into engagement with the foremost warp *b* of the sheet S², while the hold-back finger 91 has risen sufficient

to release the warp *b* from the other warps of the series *S*².

Referring more particularly to the diagrammatic Figs. 11^a and 12 to 17 inclusive for the sequence of operation of the yarn positioning instrumentalities, the position of the parts shown in Fig. 12 corresponds to those just described with respect to Fig. 10. Thus, as shown in Fig. 12, the pusher 129 has just completed its movement to the right and has carried the yarn *a* with its drop wire *W'* to the right until the yarn has snapped below the lower corner of the guide *G'* and into engagement with the vertical edge 123^b which retains it as the pusher subsequently retreats. The separator finger 116^a has already begun to move the yarn *b* to the right; the positioner 125 is approximately at the right-hand extremity of its path of movement; and behind guard *G'* the clamp 128 is nearly at the left-hand end of its path, and the looper 148 is just on the point of starting to the right, the picker block having just started to deliver a second wire from the magazine.

As the machine continues to operate, the looper 148 rapidly advances to the right as shown in Fig. 13, so as to engage the yarn *b* and to retain the latter in its advanced position as the upward swing of the separator 116^a releases it. The clamp 128 now begins to move to the right while the positioner 125, (still concealed by guard *G'*) the pusher 129 and the looper 148 move to the left at different rates (Fig. 14) until ultimately the looper 148 and the pusher 129 have retreated to the left-hand end of their paths, while the yarn *b* is held by the clamp 128 against the substantially vertical left-hand face of the positioner 125. While the yarn is thus accurately clamped at two spaced points (between the positioner and the clamp of each bridge member) the feed rolls advance the drop wire *W'* until its legs straddle the yarn *b* and it falls onto the edge 260^a of the corresponding support 259. The clamp 128 and positioner 125 now begin to separate, moving in opposite directions toward their original positions, while the pusher 129 begins again to move to the right (Fig. 16). As the pusher advances, it engages the loaded yarn *b* released by the clamp and positioner (Fig. 17) and moves it to the right until when the pusher again reaches the position of Fig. 12 the yarn *b* also snaps up into engagement with the surface 123^b, crowding the yarn *a* to the right. The parts are now in the initial position ready to repeat the above sequence of operations upon the yarn *a'* which has been released by elevation of the finger 105^a (finger 91 having already moved down to hold back the yarn of the series *S*²) and which is advanced by the separator finger 116 in the same way as was the first yarn *a*.

During the above sequence of operations the cam 166 moves the carriage so as to deliver drop wires in different planes to form a series of banks upon the warps. Thus, as illustrated in Fig. 1, drop wire *W'* has been deposited upon the first support 259 from the left-hand end of the row of supports, while wire *W*² is just about to be delivered onto the third support 259 of the row. The next wire will be delivered onto the fourth support, the next onto the second, the next onto the first, etc., thus forming a plurality of banks upon the warp yarns. By properly shaping the cam 166, the number of banks may be changed.

At each rotation of the shaft 44, the lifter lever 33 is depressed, allowing the feeler or hammer 32 to drop, if sufficient warp threads are not disposed below it to support it. After the machine has placed drop wires upon a certain number of warp threads, the separation of the threads from the main body of the warps permits the feeler or hammer 32 (when relieved of the support of the lifter 33), to drop below the level of the warp sheet. This allows the pawl 25 to engage a tooth of the ratchet wheel 21, and as the cam on the shaft 38 rotates, it depresses the lever 21 and actuates pawl 25 so as to rotate the ratchet wheel so as to turn the shaft 8 with its rolls 9 and 10, thus advancing the entire machine along the rails 14^a and 15^a so that the yarn manipulating instrumentalities are placed in position to engage a fresh group of warp yarns. Upon the next upward movement of the lifter lever 33, the feeler or hammer 32 is lifted above the plane of the warps and when the feeler is again released by depression of the lever 33, it is supported by a fresh group of warps, thus keeping the pawl 25 out of engagement with the ratchet 21 until this new group of yarns is exhausted, whereupon the advancing movement of the machine is repeated.

During the operation of the machine, the spring 183^a keeps the follower 165 in contact with the carriage actuating cam 166, while the spring 272 constantly presses the block 262 against the bank *B* of wires in the magazine, urging the latter toward the picker block so that the latter is able to pick off the endmost wire at each downward stroke. As above described if, for any reason, a drop wire fails to advance properly between the feed rolls, the latter approach each other and the machine is automatically stopped, so that the operator may receive notice that the machine is not properly functioning and may take the necessary steps to restore it to operative position.

While I have herein disclosed certain desirable arrangements for effecting the results attained, I wish it to be understood that the invention is not necessarily limited either by the exact parts here illustrated, or to

specific relative arrangement shown, and that equivalents may be substituted for the mechanisms or elements herein disclosed without departing from the spirit of the invention. It is further to be understood, as above suggested, that the cam 166 may be so arranged as to dispose the drop wires in a greater or lesser number of banks, and further that while I have here shown two separator fingers 116 and 116^a which act alternately, a single finger or a number greater than two may be employed with corresponding changes in the gearing for driving the separator finger shaft.

15 I claim:

1. A machine for associating detached loom elements with warp yarns comprising a magazine and means for moving the magazine relatively to the warp yarns including resilient means tending to move the magazine in one direction and power driven means for moving it in the opposite direction.

2. A machine for associating detached loom elements with warp yarns comprising a magazine for such elements, means for moving the magazine bodily with reference to the warp yarns whereby to deposit successive elements at different positions lengthwise of adjacent yarns, said means comprising adjustable parts whereby the length of travel of the magazine may be varied.

3. A machine for associating drop wires with warp yarns comprising a magazine for holding a series of drop wires, a movable carriage for the magazine, a lever having a cam follower, a link of adjustable length connecting the lever to the carriage, a cam element engaging the cam follower for swinging the lever, and means adapted to hold the cam follower always in engagement with the cam element.

4. A machine for depositing drop wires upon warp yarns comprising an elongate magazine for holding a series of said wires, said magazine being movable, a cam for moving the magazine in one direction, and yielding means tending to move the magazine in the opposite direction.

5. A machine for depositing drop wires upon warp yarns comprising an elongate magazine for holding a series of said wires, a movable carriage for the magazine, a rotary cam adapted to move the carriage in one direction to any of a plurality of different positions, and means tending to move the carriage in the opposite direction comprising a cable attached to the carriage and means for yieldingly tensioning the cable.

6. A machine for depositing drop wires upon warp yarns comprising a main frame having guide rails, a magazine carriage mounted to move along said rails, the carriage having means for supporting a series of drop wires, means at one end of the mag-

azine carriage for picking off wires one by one from the end of the series and for successively delivering such wires to selected warp yarns, a follower member engaging the drop wire at the opposite end of the series, a spring actuated drum mounted upon the carriage, a cable engaging the follower member and having a portion wound upon the drum whereby the latter constantly urges the follower into contact with the drop wire to compact the series of wires, a second spring actuated drum, a cable attached to the carriage and having a portion wound about the latter drum whereby the latter constantly tends to move the carriage in one direction, and power actuated means for moving the carriage in the opposite direction.

7. A machine for associating detached loom elements with warp yarns comprising a movable carriage, a magazine supported thereby, means moving with the magazine for discharging such elements in orderly sequence therefrom, and means for actuating said discharging means comprising an elongate drive pinion having its axis parallel to the path of movement of the carriage, and a gear supported by the carriage, said gear moving with the carriage lengthwise of the pinion but meshing with the latter in all positions of the carriage.

8. A machine for depositing drop wires upon warp yarns comprising a main frame and an elongate drive pinion carried by the main frame, a carriage movable in a path substantially parallel to the axis of the pinion, the carriage comprising means for supporting a series of drop wires, means mounted upon the carriage for delivering wires one by one from the magazine, said delivery means comprising an actuating gear supported by the carriage and which meshes with the elongate drive pinion in all positions of the carriage.

9. A machine for associating detached loom elements with warp yarns comprising a magazine for such elements, means for delivering such elements one by one from the magazine, a pivoted chute for guiding the advancing elements as delivered from the magazine, and means for moving the chute from an initial position in which its active surface is substantially parallel to the path of the advancing element at the beginning of its advance to a position in which the active surface of the chute is inclined with respect to said initial position as the element completes its advance.

10. A machine for depositing drop wires upon warp yarns comprising a main frame, a movable carriage supported thereby, said carriage being movable in a path parallel to the warp yarns and comprising means for holding a series of drop wires and for delivering one wire at a time from said series,

means for moving the carriage successively to each of a plurality of predetermined positions whereby to place the wires in distinct banks upon the warp yarns, spaced 5 supporting fingers carried by the main frame, said fingers corresponding to the positions of the several banks of drop wires to be formed and extending transversely of the warp yarns, and means for guiding the 10 advancing end of a drop wire as it is delivered so as to cause its legs to straddle a corresponding supporting finger.

11. A machine of the class described comprising a stop lever, an actuator for moving the stop lever to stop the machine, means for moving the actuator at regular intervals, the path of the actuator normally being such that it does not operate the stop lever, and means for changing the path of movement 20 of the actuator so that when moved it operatively engages the stop lever thereby to stop the machine.

12. A machine for depositing drop wires upon warp yarns comprising an elongate 25 magazine for holding a series of said wires, means for delivering wires one by one from the magazine and for guiding the delivered wire onto a warp yarn, an electric motor for actuating the parts, said machine comprising 30 a stop element for cutting off current from the motor, a rocker lever having an actuator member engageable with the stop element to operate the latter, a moving support for the rocker lever, means for moving the rocker 35 lever at predetermined intervals during the operation of the machine, means for so positioning the rocker lever support during orderly operation of the machine as to prevent operative engagement of the actuator member 40 with the stop element, and means for so moving the support upon failure of the drop wire properly to deliver from the magazine as to permit the actuator member to engage the stop element.

45 13. A machine for depositing drop wires upon warp yarns comprising an elongate magazine for holding a series of said wires, a movable carriage for the magazine, a rotary cam adapted to move the carriage in one 50 direction, said cam having in succession a plurality of active portions of different radii, and means tending to move the carriage in an opposite direction comprising a spring actuated drum and a cable connecting 55 the carriage and drum.

14. A machine for associating detached loom elements with warp yarns comprising a rotary shaft, yarn separator fingers carried by the shaft, a pair of levers each carrying a yarn holdback finger and a cam follower, and cam means on said shaft engageable with said cam followers for causing the holdback levers to move alternately toward operative position.

65 15. A machine for depositing drop wires

upon warp yarns comprising a pair of supports spaced lengthwise of the warp yarns, each support carrying a yarn pusher, a yarn clamp and a yarn positioner, a lever carried by each support for actuating the pusher, clamp and positioner, each such lever having a cam follower, a drive shaft, and a pair of substantially like cams actuated by the shaft, each cam engaging the cam follower of one of said levers respectively 70 whereby rotation of the shaft actuates the pusher, clamp and positioner of the two supports simultaneously.

16. A machine for associating drop wires with warp yarns comprising a magazine for 80 such wires, means for delivering wires one by one from the magazine, a support for receiving the wire as delivered, means for relatively deflecting the legs of the advancing wire to permit them to straddle the support, 85 and a guard member engageable with one leg at least of the advancing wire to insure its proper deposit upon the support.

Signed by me at Lawrence, Massachusetts, this 17th day of August, 1929.

SEBASTIANO MAGNANO.
